UNITED STATES PATENT OFFICE.

JOHN E. MILLER, OF WASHINGTON, PENNSYLVANIA, ASSIGNOR, BY DIRECT AND MESNE ASSIGNMENTS, OF ONE-HALF TO DUNCAN & MILLER GLASS COMPANY, OF WASHINGTON, PENNSYLVANIA, A CORPORATION OF PENNSYLVANIA, AND ONE-HALF TO UNITED STATES GLASS COMPANY, OF PITTSBURGH, PENNSYLVANIA, A CORPORATION OF PENNSYLVANIA.

GLASSWARE AND METHOD OF DECORATING THE SAME.

1,178,256.

Specification of Letters Patent.

Patented Apr. 4, 1916.

Application filed July 24, 1915. Serial No. 41,714.

To all whom it may concern:

Be it known that I, JOHN E. MILLER, a citizen of the United States, and resident of Washington, in the county of Washington and State of Pennsylvania, have invented certain new and useful Improvements in Glassware and Methods of Decorating the Same, of which the following is a specification.

10 The embellishing of articles of glassware by providing the surfaces thereof with depressed ornamental configuration has heretofore been accomplished both by pressing and by cutting. When pressed, the configuration is impressed in the surface of the article simultaneously with pressing the latter. As such articles are ordinarily fire-polished, the pressed configuration must be sufficiently deep or pronounced to maintain 20 its form notwithstanding the appreciable melting of the surface incident to fire finishing. It is not practical to impart fine or very shallow ornamentation by pressing for the reason that it is difficult to maintain in 25 the mold sharp and clear lines of fine or shallow character, and for the further reason that the operation of fire finishing tends to blur and efface such fine or shallow configuration. Hence, the only effective way to 30 apply the latter is to cut the same into the surface of the glass after the article has been fire polished.

The primary purpose of the present invention is to utilize and so combine these 35 two methods of embellishing a glass article as to provide a grade of ware intermediate so-called pressed glass and cut glass wherein those portions of the embellishment that are unimpaired by the fire finishing operation 40 are given their ultimate form simultaneously with pressing the article, and then after the latter has been fire finished the remainder of the embellishment, *i. e.*, those portions too shallow or too delicate to withstand the fire finish, are cut into the surface. And in those types of ornamentation in 45 which both forms of embellishment are utilized in the same configuration, the pressed and cut portions are caused to blend

one into the other in such manner as to 50 render them not readily distinguishable. When so blended the somewhat greater brilliancy of the cut portion tends to increase the luster of the pressed portion with which is immediately associated, and the result 55 is that a rich and ornate type of surface configuration is provided at small cost as compared with an all-cut article.

The operation of cutting always leaves the cut surface white or opaque, and the process 60 of grinding and polishing the cut surfaces to restore their transparency and to develop the luster characteristic of cut glass is a laborious and expensive operation. With the kind of ornamentation herein proposed, the 65 pressed portion of the configuration is not dimmed or blurred at any time, but on the contrary, its luster is increased by the fire finishing operation. It is, therefore, only necessary to grind and polish the lighter 70 and shallower portions of the configurations that can be effectively formed only by cutting. And as to these, some or all may remain opaque in accordance with the decorative scheme that may include more or less of 75 the frosted or opaque effect.

The decorative scheme of the present invention has proven very effective particularly in that type of ornamentation in which the pressed or deeper portions are of such 80 design as to provide surfaces which produce prismatic effects and in which the formation of lines liable to be blurred by the fire-finishing operation are, as far as possible, avoided. While the invention is not 85 limited in this regard, the best results are had when the precautions noted are observed.

For the purpose of illustrating the invention, I have shown in Fig. 1 of the accompanying drawings a portion of a shallow nappy or plate in which the relatively deep portions of a decorative scheme are shown in the outer surface thereof, the same having been pressed simultaneously with pressing the article, the mold, not shown, being of proper configuration. Fig. 2 is a similar view of the same portion of the article show-

ing the finer or more shallow portions of the ornamentation which have been applied by the ordinary processes of cutting. Figs. 3, 4 and 5 are fragmentary sectional views taken on lines 3—3, 4—4 and 5—5, respectively, of Fig. 2.

Referring to the drawings, 2 designates a portion of a glass article to be embellished, and 3 are parts of the configuration that are 10 of such form and of sufficient depth to permit of being formed by pressing. The article 2, commonly known as a blank, and the pressed configuration 3 are formed by the usual mold and plunger manipulation 15 well known in the glass art. Following this blank-pressing operation, the blank is stuck up on a punty or held in a snap and exposed to a fire-finishing flame which melts the surfaces to such an extent as to impart there- 20 to a fire-finish or polish. This operation is ordinarily accomplished in a glory-hole furnace and, like the pressing step, is a fa- 25 miliar procedure in every glass house in which pressed tableware is produced.

25 After the blank has been fire-finished, the remainder of the configuration is cut there- 30 on. In the most economic practice the cut portions are the finer or shallower parts of the configuration, such for instance as stems 35 4 for the pressed leaves or petals 3 of the ornamentation here illustrated. Also, the embellishment may be elaborated by cutting the flower-like figures, such as shown at 5, the same being provided with a cut stem 4 to harmonize with the combined spray and flower design.

The operation of cutting leaves the cut 40 surface opaque or of a frosted appearance which is represented by the shading of the petals of flower or blossom 5. And the same 45 frosted effect is characteristic of all of the cut lines 4 here shown, the frosting having been obliterated by subsequent grinding and polishing. It will be of course understood 50 that the frosted effect may be permitted to remain in any cut portion of the design in which such effect is desired, and to that extent decreasing the cost by eliminating the grinding and polishing necessary to re- move it.

It is characteristic of the invention that 55 those portions of the configuration that are not blurred or harmfully affected by the fire-finishing operation are produced and given final form by the initial pressing step and require no further work, and that only such portions of the configuration are cut as will not effectively withstand the heat of the glory hole. It will be understood, how- 60 ever, that deeper portions of the design may be formed entirely by cutting, at the option of the manufacturer.

By utilizing both pressing and cutting in

the production of a surface configuration, a highly decorative grade of ware is pro- 65 duced at comparatively small cost in which the major portion of the work is accom- plished in the mold and in which the ef- fective characteristics of both pressing and cutting are so combined as to produce a 70 comparatively inexpensive glass article of high artistic quality.

I claim:

1. A glass blank having fire-polished de- 75 pressions so located as to form the deeper portions of an incomplete decorative figure which may be completed by cutting.

2. A glass article embellished with a de- 80 pressed decorative figure, the deeper portions of which have fire-finished surfaces and the shallower portions of which are cut.

3. A glass article having ornamental de- 85 pressions of different depths, the surfaces of the deeper depressions being fire-finished and the surfaces of the shallower de- pressions being cut, the deeper and shallower de- pressions combining to produce a complete decorative figure.

4. The method herein described of dec- 90 orating a glass article, consisting in forming the surface of such article with ornamental depressions, fire-finishing the article includ- ing the surfaces of said depressions, and cutting the article with such cutting combining with the fire-finished depressions to com- 95 plete a decorative figure.

5. The method herein described of dec- 100 orating glassware, consisting in forming an article with relatively deep surface de- pressions, fire-finishing the article, and cutting surfaces of the article closely adjacent to the said depressions and with said depressed and cut surface portions combined in the same decorative figure.

6. The method of forming and embellish- 105 ing a glass article consisting in shaping the article and simultaneously forming de- pressions in the surface thereof, fire-polishing the article including said depressions, and completing the embellishment by cutting 110 other depressions in such surface which combine with the fire-polished depressions to complete a decorative figure.

7. The method of forming a glass article and embellishing the same with depressed 115 configurations having relatively deep and relatively shallow portions, consisting in shaping the article and simultaneously forming therein the relatively deep portions of the configuration, and then completing 120 the embellishment by cutting the relatively shallow portions of the configuration.

8. The method of forming a glass article and embellishing the same with surface config- 125 uration, a portion of the configuration being of a character to withstand fire-finish

and a portion thereof of a character not to withstand fire-finish, consisting in shaping the article by pressing and simultaneously pressing and imparting final form to that portion of the configuration that will withstand fire-finishing, fire-finishing the pressed and partially embellished article, and completing the embellishment by cutting the

portion of the configuration that will not withstand fire-finishing.

In testimony whereof I affix my signature in presence of two witnesses.

JOHN E. MILLER.
